DESIGN FOR A PULL TAB FOR SLIDE FASTENERS

Noel J. Poux, Meadville, Pa., assignor to Talon,
Inc., Meadville, Pa., a corporation of Pennsylvania

Application October 14, 1938, Serial No. 80,448

Term of patent 14 years

To all whom it may concern:

Be it known that I, Noel J. Poux, a citizen of the United States, residing at Meadville, in the county of Crawford and State of Pennsylvania, have invented a new, original, and ornamental Design for a Pull Tab for Slide Fasteners, as shown, of which the following is a specification, reference being had to the accompanying drawing, forming a part thereof.

In the drawing:

Fig. 1 shows a face view of a pull tab for slide fasteners;

Fig. 2 shows a side view of the same.

The distinguishing feature of my design is a raised portion giving somewhat the appearance of an arch in side view.

I claim:

The ornamental design for a pull tab for slide fasteners, substantially as shown and described.

NOEL J. POUX.
